UNITED STATES PATENT OFFICE.

MORRIS SCHWARTZ, OF CHICAGO, ILLINOIS, ASSIGNOR TO AMERICAN FLANGE & MANUFACTURING CO., OF CHICAGO, ILLINOIS, A CORPORATION OF ILLINOIS.

BUSHING STRUCTURE.

Application filed July 21, 1926. Serial No. 123,923.

My invention relates to bushings and their supports found in such structures, for example, as barrels where the bushings serve to receive plugs or bungs which are screwed 5 thereto. My invention has for its object the provision of improved means for obstructing rotation of the bushing when the bung is being turned.

In carrying out my invention, the sheet metal member which carries the bushing is formed with a circular rim portion angular to the body portion and surrounding a circular opening formed through said member, said body portion of said member being 10 dished adjacent said rim portion to form a pocket having shoulders at its ends. The interiorly threaded bushing has a body portion surrounded by the rim portion of the aforesaid sheet metal member, a returned 15 portion upon the exterior of and spaced apart from the body portion of the bushing, said rim portion extending into the space between said body and returned bushing portions, said bushing having a second portion returned upon the first returned portion 20 toward the connection of the latter and itself received, where connected with the first returned bushing portion, in the aforesaid pocket and engaging the aforesaid shoulders 25 30 to obstruct turning movement of the bushing, the unconnected rim of the bushing body portion desirablylapping the base of the rim portion of the aforesaid sheet metal member. In the preferred embodiment of the invention, the pocket in the sheet metal member 35 surrounds the rim portion of this member, this pocket being outwardly bulged away from the side of the rim portion to widen the pocket at one portion thereof, shoulders being formed at the ends of the bulged portion 40 of the pocket. The first aforesaid returned portion of the bushing, therefore, surrounds and is spaced apart from the body portion of the bushing and the aforesaid rim portion of the sheet metal member carrying 45 the bushing, this rim portion extending into space between this returned bushing portion and the body of the bushing.

The invention will be more fully explained 50 in connection with the accompanying drawing in which Fig. 1 is one face view of a portion of a sheet metal member equipped in accordance with my invention; Fig. 2 is a side view of the structure shown in Fig. 1 55 with the bushing and plug or bung in place;

Fig. 3 is a sectional view of the structure shown in Fig. 2, on a larger scale; Fig. 4 is a view taken generally on line 4-4 of Fig. 2, on a larger scale; Fig. 5 is a perspective view of the complete structure of my invention in its preferred embodiment; Fig. 6 is a perspective view similar to Fig. 2 with the bushing omitted; and Fig. 7 is a perspective view of the preferred form of bushing structure.

The sheet metal member 1, illustrated, may form a part of the structure which is to be supplied with a bushing, such as the end or other wall of a metallic barrel or container. This metal member is formed with a generally circular rim portion 2 which is angular to the body portion of the sheet metal member and which rim portion surrounds a circular opening formed through said member. The body portion of said sheet metal member is dished around said rim portion to form a pocket 3. This pocket is outwardly bulged away from the side of the rim portion to widen the pocket at one portion thereof, as indicated at 4, shoulders 5 being formed at the ends of the bulged portion 4 of the pocket. The bushing which is to be assembled with the sheet metal member 1 is formed of metal and has an interiorly threaded body portion 6 surrounded by the rim portion 2 of the sheet metal member. The bushing also has a returned portion 7 surrounding and spaced apart from the body portion of the bushing and also surrounding the aforesaid rim portion 2. The bushing is U-shaped in cross section at its returned portion and body portion, the rim portion 2 being received in the space between said body and returned bushing portions, said returned bushing portion 8 being received in the aforesaid pocket.

As illustrated, the returned bushing portion 7 is a continuous ring which carries a second returned bushing portion 8 which is a segment of a ring. This bushing portion 8 is returned upon the bushing portion 7 toward the rim of the latter which is integrally connected with one rim of the threaded body portion 6 of the bushing. The bushing portion 8 is received, where connected with the bushing portion 7, in the bulged portion 4 of the pocket that surrounds the rim 2 of the sheet metal member 1. The ends of the bushing portion 8 abut against the shoulders 5 at the ends of the pocket en-

largement 4 to prevent the bushing from being turned as the bung 9, threaded into the bushing, is turned. The outer wall portions of the pocket where the pocket is outwardly bulged and where it is not bulged are formed to offer no material resistance to the turning movement of the bushing. The advantage of the second returned bushing portion 8 resides in the fact that the greater depth of the metal of the bushing measured axially of the bushing is engaged with the end shoulders 5 of the pocket than would be presented for engagement with these shoulders were this second returned bushing portion absent. To gain this same effect with no second returned bushing portion 8, the thickness of the blank out of which the bushing is formed would have to be increased to an extent that is not permissible in die practice. The body portion of the bushing and the first and second returned portions thereof are annular and concentric with the rim portion 2 of the sheet metal member 1, a construction which I have devised to enable the formation of the second returned bushing portion 8 by a die operation. The unconnected rim 10 of the bushing body portion is outwardly curled to lap the base of the rim portion 2 whereby the sheet metal member 1 and said bushing are permanently assembled. The bung 9 may be provided with a surrounding flange 11 which laps the bushing rim 10, the rim portion 2, and the contiguous portion of the sheet metal member 1 which surrounds the rim portion 2. A sealing gasket 12 may be interposed between the flange 11 and the contiguous portions of the bushing and sheet metal member.

The arcuate returned bushing portion 8 may be spaced as far apart from the returned bushing portion 7 as may be desired to afford any requisite resistance to the turning of the bushing, the bulging portion 4 of the pocket being correspondingly widened.

Changes may be made without departing from the invention.

Having thus described my invention, I claim:

1. The combination with a sheet metal member including a body portion, a circular rim portion angular to the body portion and surrounding a circular opening formed through said member, said body portion of said member being dished around said rim portion to form, with said rim, a pocket, this pocket being outwardly bulged away from the side of the rim portion to widen the pocket at one portion thereof, shoulders being formed at the ends of the bulged portion of the pocket; of an interiorly threaded bushing having a body portion surrounded by said rim portion, a returned portion surrounding and spaced apart from the body portion of the bushing and received in said pocket and surrounding the aforesaid rim

portion which extends into the space between said body and returned bushing portions, said bushing having a second portion returned upon the first returned portion toward the connected rim of the latter and itself received, where connected with the first returned bushing portion, in the bulged portion of the aforesaid pocket and engaging the aforesaid shoulders to obstruct turning movement of the bushing, the unconnected rim of the bushing body portion lapsing the base of the rim portion of the aforesaid sheet metal member, the outer wall portion of said pocket where the pocket is outwardly bulged being formed to offer no material resistance to the turning movement of said bushing.

2. The combination with a sheet metal member including a body portion, a circular rim portion angular to the body portion and surrounding a circular opening formed through said member, said body portion of said member being dished around said rim portion to form, with said rim, a pocket, this pocket being outwardly bulged away from the side of the rim portion to widen the pocket at one portion thereof, shoulders being formed at the ends of the bulged portion of the pocket; of an interiorly threaded bushing having a body portion surrounded by said rim portion, a returned portion surrounding and spaced apart from the body portion of the bushing and received in said pocket and surrounding the aforesaid rim portion which extends into the space between said body and returned bushing portions, said bushing having a second portion returned upon the first returned portion toward the connected rim of the latter and itself received, where connected with the first returned bushing portion, in the bulged portion of the aforesaid pocket and engaging the aforesaid shoulders to obstruct turning movement of the bushing, the outer wall portion of said pocket where the pocket is outwardly bulged being formed to offer no material resistance to the turning movement of said bushing.

3. The combination with a sheet metal member including a body portion, a circular rim portion angular to the body portion and surrounding a circular opening formed through said member, said body portion of said member being dished adjacent said rim portion to form, with said rim, a pocket having spaced apart shoulders; of an interiorly threaded bushing having a body portion surrounded by said rim portion, a returned portion upon the exterior of and spaced apart from the body portion of the bushing, said rim portion extending into the space between said body and returned bushing portions, said bushing having a second portion returned upon the first returned portion toward the connection of the latter with the

- bushing body portion and itself received, where connected with the first returned bushing portion, in the aforesaid pocket and engaging the aforesaid shoulders to obstruct 5 turning movement of the bushing, the unconnected rim of the bushing body portion lapping the base of the rim portion of the aforesaid sheet metal member, the outer wall portion of said pocket where the pocket is 10 outwardly bulged being formed to offer no material resistance to the turning movement of said bushing.
4. The combination with a sheet metal member including a body portion, a circular 15 rim portion angular to the body portion and surrounding a circular opening formed through said member, said body portion of said member being dished adjacent said rim portion to form, with said rim, a pocket 20 having spaced apart shoulders; of an interiorly threaded bushing having a body por-
- tion surrounded by said rim portion, a returned portion upon the exterior of and spaced apart from the body portion of the bushing, said rim portion extending into the 25 space between said body and returned bushing portions, said bushing having a second portion returned upon the first returned portion toward the connection of the latter with the bushing body portion and itself received, 30 where connected with the first returned bushing portion, in the aforesaid pocket and engaging the aforesaid shoulders to obstruct turning movement of the bushing, the outer wall portion of said pocket where the pocket 35 is outwardly bulged being formed to offer no material resistance to the turning movement of said bushing.

In witness whereof, I hereunto subscribe my name.

MORRIS SCHWARTZ.
